UNITED STATES PATENT OFFICE.

MARTHA A. NYE, OF CHICOOPEE FALLS, MASSACHUSETTS.

DESIGN FOR A BREASTPIN, &c.

SPECIFICATION forming part of Design No. 22,150, dated January 24, 1893.

Application filed August 19, 1892. Serial No. 443,538. Term of patent 14 years.

To all whom it may concern:

Be it known that I, MARTHA A. NYE, of Chicopee Falls, in the county of Hampden and State of Massachusetts, have invented a Design for 5 Breastpins and other Similar Articles, of which the following is a specification.

The drawing represents an enlarged side view of a breast-pin showing my design.

The leading feature of my design is a figure comprising an anchor, an outline or open heart superimposed on the shank of the anchor, and a cross composed in part of the shank of the anchor and in part of a cross-bar above the heart, as shown in the drawing.

I claim:

The design for breast-pins and other similar articles, substantially as herein shown and described.

In testimony whereof I have signed my name to this specification, in the presence of two 20 subscribing witnesses, this 3d day of August, A. D. 1892.

MARTHA A. NYE.
